(57) **CLAIM**

The ornamental design for a toilet as shown and described.

DESCRIPTION

FIG. 1 is a perspective view of the toilet of the present invention.

FIG. 2 is a front elevation of the toilet of the present invention.

FIG. 3 is a rear elevation of the toilet of the present invention.

FIG. 4 is a right side elevation of the toilet of the present invention.

FIG. 5 is a left side elevation of the toilet of the present invention.

FIG. 6 is a top view of the toilet of the present invention; and,

FIG. 7 is a bottom view of the toilet of the present invention. The evenly spaced broken lines and the areas within them depict portions of the toilet that form no part of the claim.

1 Claim, 7 Drawing Sheets
